UNITED STATES PATENT OFFICE.

ALEXANDER K. ALGEO, OF HOPE, NORTH DAKOTA.

WILD-OATS SEPARATOR.

1,331,608.

Specification of Letters Patent. Patented Feb. 24, 1920.

Application filed December 1, 1917. Serial No. 204,863.

To all whom it may concern:

Be it known that I, ALEXANDER K. ALGEO, a citizen of the United States, residing at Hope, in the county of Steele and State of North Dakota, have invented certain new and useful Improvements in Wild-Oats Separators, of which the following is a specification.

My invention relates to separators and 10 more particularly to that class especially adapted for separating wild oats from other grain.

The primary object of my invention resides in the provision of an improved separation means for removing wild oats from grain, including preferably a plurality of cloth aprons operating in opposite directions having scraping means associated with the under portions thereof for removing the 20 wild oats which has adhered thereto during the operation of the aprons so that the wild oats may be conveyed to a point remote from the supporting body or frame.

Another object of my invention resides in 25 the provision of an improved guarding means associated with the apron supporting body and with the upper portions of the apron to prevent the grain which is deposited upon the aprons from falling between the sides of the aprons and the inner walls of the supporting body.

A further object of my invention resides 35 in the provision of an improved means for mounting the screening means, the latter having novel means associated therewith for producing vibratory movement to the screens for agitating the grain deposited thereon, said movement being imparted thereto simultaneously with the operation of 40 the aprons, interposed between the screens.

A still further object of my invention resides in the provision of an improved fanning means mounted within the body and arranged to convey chaff and wild oats that 45 have not been separated from the good grain, by means of the agitating and separating means, to a point remote from the body.

A still further object of my invention resides 50 in the provision of a device of the character described that is simple in construction, efficient in operation and one that can be manufactured and placed on the market at a minimum cost.

55 Other objects as well as the nature, characteristic features and scope of my invention

will be more readily understood from the following description taken in connection with the accompanying drawings and pointed out in the claims forming a part of 60 this specification.

In the drawings:

Figure 1 is a side elevational view of my invention;

Fig. 2 is a longitudinal sectional view of 65 the same;

Fig. 3 is a transverse sectional view taken on the line 3—3 of Fig. 2 in the direction in which the arrow points; and

Fig. 4 is a transverse sectional view of 70 my invention taken through the same at a point slightly above the lower screen.

Referring more particularly to the drawings in which similar reference numerals designate like or corresponding parts 75 throughout the different views, I provide a preferably rectangular supporting body or frame, including preferably side pieces 1 and end pieces 2, suitably connected and supported in spaced relation from the surface 80 by means of legs 3, the forward legs being extended above the surface of the rearwardly slanting top 4 to constitute a means for facilitating the supporting of the grain receiving hopper 5 supported in an upright 85 position upon the top 4 by means of braces 6 connected to the forward legs 3 and other braces 7 connected to the sides 1 of the body. The under surfaces of the hopper are slanted toward each other and are arranged in 90 spaced relation with each other so as to allow grain to pass therethrough into the body. It is to be understood that this structure forms no essential part of the invention, being merely shown and described in this 95 manner to facilitate a thorough understanding of the invention.

In order to screen the grain and also facilitate the separation of the chaff from the grain, I have disposed a screen 8 beneath 100 the lower end of the hopper; this screen has its forward end secured to the sides of the body by suitable means, such as the rod 9. The screen is arranged in a closely spaced relation with the under surface of the top 105 and has its opposite or lower end supported by means of rods 10. The looped ends 11 of these rods are connected to the sides of the screen by means of suitable fastening devices 12, which devices are adapted to operate, in slots 13 in the upper ends of the rear legs 3. The rods 10 have their oppo-

site ends looped as at 14, and are eccentrically connected by means of fastening devices 15 to the outer surfaces of the disks 16. The disks 16 are rigidly carried on the 5 projecting ends of the shaft 17 rotatably mounted in the rear legs 3. Also supported by the rods 10, and between the side pieces 1, is the lower screen 18. The connection between the rods 10 and screen 18 consists 10 of enlargements 14' through which pass suitable fastening devices 15', the latter engaging the screen 18 and being arranged to operate in the slots 16' in the rear legs 3 for a purpose to be hereinafter described. 15 The lower screen in this instance consists essentially of a rectangular frame 19, having a reticulated means 20, preferably a screen wire disposed on the outer end thereof, the outer end of the frame extending 20 slightly downwardly and supported by means of a roller 21, rotatably mounted between the forward legs. The inner portions of the sides of the frame 19 are extended upwardly to provide supporting 25 pieces 22 for maintaining the supporting frame 23 of the inner section 24 and screen 18, which section is incidentally formed preferably of wire screen of a mesh slightly smaller than the mesh of the screening 20. 30 The frame 23 is arranged in spaced parallel relation with the frame 19 and abuts a guard 25, the latter being for a purpose to be hereinafter described, and which guard has its upper end arranged in spaced relation 35 with the rear end 2 and upper edge also in spaced relation with the said end 2, the lower end of the guard being supported upon and rigidly connected to the inner end of the frame 19. 40 A pan 26 is supported in spaced relation on the under surface of the frame 23 to receive the good grain after it has passed through the screen 24, the said pan having an opening 27 therein adjacent the outer 45 end thereof and to the under surface of which pan about the opening is connected a chute 28 by means of fastening devices 29, the said chute serving as a suitable means for conveying the good grain from the pan 50 to a receptacle positioned beneath or at a point remote from the supporting body or frame. Another pan 30 is rigidly supported on the under surface of the outer end of the frame 19 for receiving the good grain 55 which is incidentally better than the grain that enters the pan 26 for the reason that the mesh of the screening 20 is larger than that of the screening 24 carried by the frame 23. The can 30 is also provided with an 60 opening 31 which allows the grain to enter the chute 32 carried on the under surface of the pan 30 about the opening, the said chute facilitating the conveying of the grain to a receptacle beneath the frame. 65 For the purpose of separating wild oats

from good grain, I have interposed between the upper and lower screens and between the sides 1 of the body, a pair of separating aprons 33 and 34, the upper of said aprons 33 being arranged beneath the upper screen 70 and operating about drums 35 and 36, the drum 35 having one of its ends projecting through one of the sides of the body and on which reduced end is rigidly connected a cog wheel 37 for a purpose to be hereinafter 75 described. The lower apron 34 is slightly longer than the upper apron and operates about drums 38 and 39, the drum 38 having one of its ends reduced and journaled through the sides 2 to receive a cog wheel 80 40 which incidentally is arranged in mesh with the cog wheel 37 and operable thereby. In order to provide an efficient means for governing and adjusting the tension of the separating aprons 33 and 34, I have found 85 it expedient to journal the ends of the rear drums 36 and 39 in blocks 41. These blocks are slidably mounted in openings 42 that are formed in the sides and rear legs of the body. The free ends of bolts 43 are rotatably 90 secured in the blocks to provide for a more or less universal movement therebetween. The upper one of said bolts being also arranged, preferably in screw threaded engagement, with the laterally extending 95 brackets 44 carried on the sides of the rear legs adjacent the upper ends thereof. The lower one of the bolts being arranged through the rear edges of the rear legs. The heads 45, formed on the opposite ends 100 of the bolts, constitute a suitable means for rotating the bolts and causing the blocks to slide in either direction in the openings 42 to adjust the tension of the aprons. Transverse bars 42' extend between each of 105 the aprons and serve as a suitable means for facilitating the supporting of the upper portions of the aprons when heavily laden with grain, thus facilitating the operation of the aprons. 110

In order to prevent the grain that has been deposited upon the aprons from falling between the side edges of the aprons and the inner sides of the body, I have rigidly secured guarding strips 46 to the inner surface of the sides 1 by means of suitable fastening devices 47, the side strips extending laterally from the inner surface of the sides and being arranged in close relation with the upper surfaces of the aprons. 115 120

In order to remove wild oats from the separating aprons to which the wild oats adheres during the operation of the aprons, I have extended scraping bars 48 transversely of the body, the respective ends 125 thereof being secured to the inner sides of the body, and the upper edges of the bars being arranged in close engagement with the end portions of the aprons, the bars being disposed at acute angles to the lower 130

portions of the aprons and at an acute angle thereto with respect to the courses that the aprons are traveling. This arrangement of the bars facilitates the removal of the chaff 5 and wild oats from the aprons as well as the 10 depositing of the chaff and the wild oats in the chutes 49 positioned beneath each of the aprons and arranged transversely of the body, the said chutes being also arranged 15 slantingly toward the lower screen so that the wild oats will slide down the same and be conveyed toward the lower ends due to the force of gravity, the said lower ends being positioned exteriorly of one of the sides 20 so that the wild oats may be deposited in a suitable receptacle positioned therebeneath.

In the event that all of the chaff and wild oats are not removed from the grain after the latter has been deposited upon the lower 25 of the screens in a manner to be hereinafter described, I have provided my improved fanning means for conveying the chaff from the lower screen to a point remote from the body. The fanning means in this instance 30 consists of a transversely arranged and rotatably mounted shaft 50 on which is rigidly carried a sleeve, on the outer surface of which is a plurality of radially projecting blades 51. It is preferable that the blades 35 of this fan extend approximately entirely across the body so as to provide an efficient operation, or rather means for expeditiously removing the chaff and wild oats. When the fan is rotated in a manner to be herein- 40 after described, a draft is created across the bottom screen through the medium of the opening provided in the rear end by the guard 25. The fan is positioned approximately midway between the lower apron 34 and the curved forward end plate 52 and is arranged to rotate so that the blades adjacent the curved plate move upwardly with respect thereto thus causing the chaff and wild oats to be drawn from the lower screen 45 and conveyed about the curved plate from whence it is blown upwardly and out the opening provided in the upper end of the body between the top and the forward end of the body. It is of course understood that 50 if desired, means can be employed for conveying this chaff and wild oats to any desired point should it be found necessary.

In order to simultaneously operate the aprons in opposite directions and agitate the 55 upper and lower screens as well as actuate the fanning means for agitating and separating the grain that is received from the hopper 5, I have journaled the respective ends of the transverse shaft 53 through the 60 forward legs adjacent the upper ends thereof at a point in substantial alinement with the upper of the aprons, the said shaft having a large gear 54 rigidly carried by the projecting end thereof, which gear is positioned in close relation with the exterior of

one of the forward end pieces and is also arranged in mesh with the gear wheel 37. Also rigidly connected to this shaft 53 is a cog wheel 55 and handle 56, the handle facilitating the rotation of the shaft consequently 70 rotating the gear 54 as well as the gears 37 and 40. A chain 57 is trained about the cog wheel 55 and also trained about another cog wheel 58 rigidly carried on the projecting end of the transverse shaft 50 75 and it will be obvious that when the shaft 53 is rotated, the shaft 50 will be rotated, consequently causing the fan rigidly carried by the shaft 50 to be rotated for accomplishing its function. A connecting rod 59 80 having its respective looped ends pivotally connected eccentrically to the outer surface of the cog wheel 58 and one of the disks 16 through the instrumentality of the fastening device 15 constitutes a suitable means for 85 imparting a shaking or vibratory movement to the screens. This movement is facilitated through the medium of the openings provided in the rear legs, for it will be seen that when the crank 56 is actuated, the bars 11 90 will move substantially vertically causing the screens 8 and 18 to which they are connected to consequently move up and down, which screen 18, because of its connection with the rods at the openings 16' will move 95 slightly longitudinally of the body, the roller 21 facilitating the supporting of the frame of the screen 20, during this sliding movement. As the screen 8 is agitated, grain will be deposited upon the upper of 100 the separating aprons 35, said grain being prevented from falling therefrom about the sides thereof by the strips 46. The upper apron 32 will move in the direction in which the arrow points toward the forward end 105 of the body, consequently causing the grain thereon to be deposited upon the lower apron and the chaff and wild oats which adheres to the upper apron will be scraped therefrom and deposited in the chute 49 and 110 conveyed from the body. After the grain is deposited upon the lower apron 34 it is carried to the rear end of the body and deposited upon the screen 24. Wild oats will adhere to the apron 34 and be conveyed on 115 the under portion until it engages the other of the scraping bars 48 and deposited in the other of the chutes 49 and thence conveyed from the body into a suitable container, not shown. Due to the vibratory 120 movement of the said screen, some of the smaller kernels of grain fall therefrom and rest upon the pan 26 positioned therebeneath from whence kernels of grain fall through the chute 28 into a suitable receptacle, not 125 shown, positioned beneath the body. The larger kernels of grain slide from the screen 24 and fall upon the screen 20 of a larger mesh, from which screen the kernels fall between the pan 30 and thence pass through 130

the chute 32 into another receptacle positioned therebeneath for receiving the same. Should there be any chaff or other oats that has not been removed from the grain after it has reached the screen 20, the fan operating simultaneously with the screens and aprons serves as a suitable means for conveying the chaff upwardly and thence from the body.

10 A fly wheel 60 is rigidly carried on the free extended end of the transverse shaft 53 and when desired a belt 61 from a suitable source of power, not shown, may be associated therewith so as to actuate the separator.

Although I have shown and described the preferred embodiment of my invention, I desire that great stress be laid upon the arrangement of the coöperating screening, separating and fanning means for efficiently separating wild oats from grain, the said screening means being peculiarly arranged to assort or grade the grain after it has been cleaned. Attention is also directed to the novel means for simultaneously operating the screening, separating and fanning mechanism.

From the above description taken in connection with the accompanying drawings, it can easily be seen that I have provided a device that is simple in construction, containing but a few simple parts that can be cheaply manufactured and assembled and

when assembled can be placed upon the market and sold at a minimum cost.

It will be understood that the above description and accompanying drawings comprehend only the general embodiment of my invention and that various minor changes in detail of construction, proportion and arrangement of the parts may be made within the scope of the appended claims and without sacrificing any of the advantages of my invention.

Having thus fully described my invention, 45 what I claim as new and desire to secure by Letters Patent, is:—

A wild oats separator including a body, upper and lower screens mounted in the body, a plurality of separating aprons operating in opposite directions interposed between the screens, means for preventing grain from falling about the sides of the aprons, means for removing the wild oats from the aprons, means for operating the aprons and simultaneously imparting a vibratory movement to the screens, and means for conveying the cleaned grain from the body.

In testimony whereof I affix my signature 60 in presence of two witnesses.

ALEXANDER K. ALGEO.
